By R.S. & A. Lacey, Atty's.

UNITED STATES PATENT OFFICE.

JOHN HAMLIN, OF WILKES-BARRE, PENNSYLVANIA.

ANVIL.

SPECIFICATION forming part of Letters Patent No. 278,237, dated May 22, 1883.

Application filed October 26, 1882. (No model.)

To all whom it may concern:

Be it known that I, JOHN HAMLIN, a citizen of the United States, residing at Wilkes-Barre, in the county of Luzerne and State of Pennsylvania, have invented certain new and useful Improvements in Anvils; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention has relation to improvements in anvils for smiths' use, and has for its particular object to provide an anvil for forming the toe and heel calks, as will be described.

It consists, essentially, in constructing the anvil with a flat top and forming its front with one vertical and one inclined or beveled face, and in other improvements, as will be herein-after fully described, and specifically pointed out in the claims.

In the drawings, Figure 1 is a front view, and Fig. 2 is a plan view, of my anvil; and Fig. 3 is a detail perspective view, as will be described.

a is the anvil proper, rested on the upright or support *a'*, which is mounted on a block, *a²*, or other stand, as may be desired. For convenience of reference I denominate the side of the anvil marked *x*, the "rear" side, and the side marked *y*, the "front" of the anvil.

b is the top face of the anvil. It is arranged in a horizontal plane, and the face *b²* is arranged perpendicularly to the face *b*, as shown.

b' is the inclined face. It is arranged on the front of the anvil, as is the face *b²*, and it is arranged vertically, laterally, and longitudinally at an angle to the face *b²*, and is arranged at a suitable angle with reference to the top horizontal face *b*, to give the proper incline to the calks, as will be described. It will be seen that the lines of connection of faces *b' b²* with the top face, *b*, form a V shape, as shown in Fig. 1, and the back *x* of the anvil is formed of two vertical faces, *b³ b⁴*, the face *b³* being parallel with the face *b²*, and the face *b⁴* being longitudinally parallel and laterally at angle 50 to the face *b'*.

The operation of my invention and the ad-

vantages incident to the construction before set forth I will now describe.

The advantage and necessity of the calks are obvious, and the angle between the faces *b'* and *b* of the anvil is equal to that between the calks and the main portion of the shoe.

The shoe, grasped by tongs, is held flat against the face *b'* with enough of its ends projected above the top *b* to form the calks. The face *b²*, being carried back from the face *b'*, is out of the way of the tongs in which the shoe is grasped. The smith stands in rear of the anvil, and, it being depressed or made narrow at the middle, where most of the blows are administered, permits the end of the hammer-handle to be brought below the top of the anvil and admits of the "drawing" stroke, which is the most advantageous one in forming calks of horseshoes or similar constructions. The vertical face *b²* is useful in certain seasons for forming calks on old shoes that do not require any angle.

The back of the anvil, being depressed in the center and formed in V shape, is advantageous, as described; but it will be understood that good results may be had where it is made straight across, though the smith will not have the same convenience in making the drawing stroke.

Having thus described my invention, what I claim, and desire to secure by Letters Patent, is—

1. The anvil constructed with a flat top, *b*, and having its front side composed of the vertical face *b²* and the beveled or inclined face *b'*, the face *b'* being arranged with reference to the face *b²* and top *b* substantially as described and shown.

2. The anvil *a*, having the flat top *b* and the vertical and inclined front faces, *b² b'*, and having its rear side depressed in the center, forming, substantially, a V shape, as and for the purposes specified.

In testimony whereof I affix my signature in presence of two witnesses.

JOHN HAMLIN.
